UNITED STATES PATENT OFFICE.

WILLIS J. PEELLE, OF CHICAGO, ILLINOIS.

SCREW CAP.

Application filed January 13, 1923. Serial No. 612,472.

To all whom it may concern:

Be it known that I, WILLIS J. PEELLE, a citizen of the United States, residing at Chicago, in the county of Cook and State of Illinois, have invented a certain new and useful Screw Cap, of which the following is a specification.

The invention pertains to screw caps or closures for glass containers, such as packer's jars, and the general aim of the invention is to facilitate the removal of screw caps from the jars.

Screw caps are now commonly applied to their containers by automatic capping machines which fasten the caps onto the jars so tightly as to render it exceedingly difficult to remove them. The object of my invention is to provide a construction for the cap such that its screw-threaded fastening flange may be readily expanded so as to effect a loosening of the cap and thus render possible its easy removal.

I attain this object by forming enlargements or protuberances in the flange of the cap transversely of the screw thread and at spaced intervals throughout the circumference of the cap, the portions thus formed serving when flattened out to increase the effective circumference of the flange and also effecting a release of the grip of the thread upon the thread of the container.

In the accompanying drawings, Figure 1 is a side elevational view of a cap constructed in accordance with my invention and showing outward enlargements in the flange of the cap formed upon the top as well as the bottom of the thread and arranged in alignment. Fig. 2 is a horizontal sectional view taken in the plane of line 2-2 of Fig. 1. Fig. 3 is a side elevational view showing the protuberances alternating on the top and bottom of the thread. Fig. 4 is a horizontal sectional view taken in the plane of line 4-4 of Fig. 3. Fig. 5 is a fragmentary sectional view corresponding to Fig. 4, but showing the top of the thread provided with an inward enlargement.

My invention is applicable to screw caps of the usual and ordinary construction, consisting of a main or top wall 7 having a peripheral flange 8 which is shaped by means of suitable dies to form a rounded thread appearing both upon the inside and outside of the flange, the top of the thread on the inside of the cap forming the bottom of the thread on the outside of the cap, and vice

versa. For convenience I herein refer to the top and bottom of the thread viewed from the inner side of the flange, the top being designated by the numeral 9 and the bottom by the numeral 10. The top of the thread thus engages with the neck of the jar between adjacent convolutions of the thread formed thereon, and the bottom of the thread engages with the top of the jar

60

65

thread. The flange 8 as shown in Fig. 1, is provided at spaced points throughout its circumferences upon its inner side, with recesses or grooves extending transversely of the thread and forming two outwardly extending protuberances 11 and 11^a, one in the bottom and one in the top of the thread but in longitudinal alignment. In the construction shown in Fig. 3 separate grooves or recesses, made of a length to extend across the top and bottom only of the thread form outwardly extending protuberances 12 and 12^a spaced apart about the circumference of the thread in alternate arrangement. While the enlargements thus formed project outwardly, it will be obvious that the construction may be reversed. Thus in Fig. 5 I have shown an inward enlargement 13 formed in the top only of the thread.

75

80

85

It will be observed that the effect of the enlargements thus formed in the thread of the cap is to provide spaces between the cap and the thread 14 on the neck of the container, and that by simply tapping upon the outward protuberances 11, 11^a and 12, 12^a, or upon the top or the thread at the sides of the inward enlargement 13, sufficiently to produce a flattening effect, the metal will be expanded and thus effect a release of the grip of the flange upon the neck of the vessel.

90

Obviously the raised portions or protuberances may be spaced about the circumference of the flange as desired. The number thereof employed will depend upon the size and depth of the cap, the thickness of the metal employed in the cap, the size of the thread, and the size of the enlargement.

95

It will be seen that I have produced a cap which possesses a distinct advantage over the ordinary screw cap, while the cost of manufacture is not materially increased.

100

I claim as my invention:

1. A cap or closure having a flange formed with a screw thread whereby it may be screwed onto the threaded neck of a

110

2
container, the flange having formed therein at spaced points in its periphery enlargements in the top and bottom of the thread adapted when flattened to increase the effective circumference thereof.

2. A cap or closure having a flange formed with a screw thread whereby it may be screwed onto the threaded neck of a container, the flange having formed therein at spaced points in its periphery protuberances in the top of the thread adapted when flattened to increase the effective size of the thread circumferentially of the container.

3. A cap or closure having a flange formed with a screw thread whereby it may be screwed onto the threaded neck of a container, the flange having formed therein at spaced points in its periphery protuberances in the bottom of the thread adapted when flattened to increase the effective size

of the thread circumferentially of the container.

4. A cap or closure having a flange formed with a screw thread whereby it may be screwed onto the threaded neck of a container, the flange having formed therein at spaced points in its periphery outward enlargements in the bottom of the thread adapted when flattened to loosen the cap from the container.

5. A screw cap made of sheet metal and having its thread interrupted by an enlargement projecting out of the normal path of the thread and adapted to be flattened whereby to increase the effective circumference of the thread and release its grip upon the thread of the container.

In testimony whereof, I have hereunto affixed my signature.

WILLIS J. PEELE.
